UNITED STATES PATENT OFFICE.

WILLIAM EVANS AND NEIL MCARTHUR, OF STURGEON FALLS, CANADA.

CATTLE-GUARD.

SPECIFICATION forming part of Letters Patent No. 660,495, dated October 23, 1900.

Application filed January 6, 1900. Serial No. 681. (No model.)

To all whom it may concern:

Be it known that we, WILLIAM EVANS and NEIL MCARTHUR, subjects of Her Majesty the Queen of Great Britain, residing at Sturgeon Falls, county of Nipissing, Province of Ontario, Canada, have invented certain new and useful Improvements in Cattle-Guards; and we do hereby declare that the following is a full, clear, and exact description of the invention, such as will enable others skilled in the art to which it appertains to make and use the same.

This invention relates to cattle-guards of that class which are designed to be placed upon a railroad-track to prevent cattle from passing along the track or from getting from one field into another by means of the track.

The object is to provide a cattle-guard of this character which is simple in construction, strong and durable, effective in operation, and which can be manufactured at a moderate cost.

To these ends the invention consists in a cattle-guard constructed substantially as hereinafter illustrated and described, and defined in the appended claims.

Referring to the drawings, in which similar letters of reference indicate similar parts, Figure 1 is a view in perspective of a section of track to which is applied a cattle-guard constructed in accordance with this invention. Fig. 2 is an enlarged longitudinal sectional view with certain parts of the track and the improved cattle-guard broken away, the plane of the section being taken near one of the track-rails and through parts of the cattle-guard, so as to show the links which form the pivotal support for the guard proper, said links being themselves pivoted on supporting-plates fastened to the sleepers.

In the drawings, A represents a section of a railroad, between the rails of which is pivoted a platform A', which is constructed, preferably, in the form of a series of spaced bars a, solidly united in any suitable manner. As shown, the platform is secured to a rod a', which is pivotally connected by means of straps a² to a beam a³, secured to one of the sleepers. It is evident, however, that any suitable pivotal connection other than that shown may be employed, if desired.

At the extremities of the bars a are curved

fingers or hooks a⁴, which are adapted to rest upon and engage the rod b of the guard B and, if desired, one or more of said bars a 55 may be provided with a spring-plate a⁵, which is adapted to engage the under side of the bar b and prevent the accidental disengagement of the platform A.

The guard B is constructed, preferably, of a rock-plate B', which is provided at its rear portion with the rod b and at its front portion with the bar b', to which the rods b² are firmly bolted. The portion of the rock-plate B' between the rod b and the bar b' is downwardly curved and preferably is composed of a series of spaced strips b³ for the purpose of combining lightness with strength. The series of spaced strips b³, which constitute the curved rock-plate B', have secured thereto in any suitable way a transverse horizontal rod b⁴. As shown by Fig. 2 of the drawings, a strap or link b⁵ has one end loosely fitted on or looped around this rod b⁴, and this link or strap is extended away from the rock-plate, 75 the free end of said link or strap b⁵ being connected by a pivot or pin to the upstanding ears or flanges on a metallic plate which spans two of the sleepers and is firmly secured thereto, substantially as shown by Fig. 80 2. There are two of these links or straps b⁵ employed, one near each end of the rock-plate and the rod b⁴, and these plates or straps are adapted to rest on their supporting-plates or on studs extending upwardly 85 therefrom, as shown by Fig. 2, whereby the links or straps in the normal position of the parts are adapted to serve as the pivotal support for the rock-plate. The rods b² are received in their lowered position between the spaced timbers D, secured between the rails in front of the guard B, and suitable stops d may be arranged between said timbers to prevent the rods from descending too far.

When cattle attempt to pass along the track, they must first step upon the platform, which is immediately pressed down, causing the guard B to fly up and prevent their further passage. As soon as the weight is removed from the platform the guard falls down by gravity out of the way of passing trains. By reason of the loose connection of the straps b⁵ all injurious jarring of the guard as it flies up is prevented. When the plat-

form is fully depressed, the front portion of the curved rock-plate is adapted to bear upon one of the sleepers, and the links or straps ^{b5} are free to be raised slightly in order that 5 the guard may assume an approximately-vertcal position.

While we have herein shown a preferred form of carrying our invention into effect, yet we do not desire to limit ourselves to such preferred details of construction, but claim the right to use any and all modifications thereof which will serve to carry into effect the objects to be attained by this invention in so far as such modifications and 15 changes may fall within the spirit and scope of our said invention.

We claim—

1. A cattle-guard, comprising a pivoted platform; a pivoted guard adapted to be engaged by said platform and elevated by the downward movement of said platform; and straps loosely pivoted to a suitable support 2c

and pivotally connected to said guard, said straps being adapted to bear upon a suitable support under strain and provide a fulcrum ²⁵ for said guard, substantially as described.

2. A cattle-guard, comprising a platform pivoted at its rear end to a suitable support and having at its forward end curved fingers; a guard having a curved rock-plate at its rear ³⁰ end adapted to be operatively engaged by said curved fingers, a rod secured to the lower portion of said rock-plate; straps loosely secured to a suitable support and pivotally connected to said rod, substantially as 35 described.

In witness whereof we have hereunto set our hands in the presence of two witnesses.

WILLIAM EVANS.
NEIL MCARTHUR.
